(57) CLAIM

The ornamental design for a personal financial organizer, as shown and described.

DESCRIPTION

FIG. 1 is a front elevation view of a personal financial organizer showing my new design;

FIG. 2 is a rear elevation view;

FIG. 3 is a right side elevation view;

FIG. 4 is left side elevation view;

FIG. 5 is a top plan view;

FIG. 6 is a bottom plan view;

FIG. 7 is a front elevation view of a personal financial organizer open to a first section; and,

FIG. 8 is a front elevation view of a personal financial organizer open to a second section.

The broken lines are for illustrative purposes only and form no part of the claimed design.
